C. N. WEEMS

REFLECTOR

Filed August 13, 1925

UNITED STATES PATENT OFFICE.

CHESTER N. WEEMS, OF ATLANTA, GEORGIA.

REFLECTOR.

Application filed August 13, 1925. Serial No. 49,892.

This invention relates to an improved reflector for headlights which will function without the use of diffusing lens placed in the path of the light and will spread and 5 diffuse the headlight beam in horizontal directions without materially distorting the headlight beam in vertical direction.

The invention is particularly designed for use on such reflectors which, in themselves, 10 will direct the path of light beam downward in relation to the axis of the reflector and spread the light beam so as to give broad illumination on the roadway and at the same time so diffuse the light in a horizontal direction 15 that a definite light pattern with sharp outline will not result. There will, however, be produced a soft, diffused field of light on the roadway and at the same time the beam will not be materially diffused or spread in 20 vertical direction, thus preventing any portion of the light beam striking above the level of the reflector.

The invention consists in placing flattened portions and arranging them radially with 25 respect to the reflector axis and disposing them in such a manner on the reflector surface as to produce the desired result.

It is understood that my invention may be used with any reflector of the parabolic type 30 but I prefer to use it and I have illustrated it on the type of offset reflector described in my United States Patent #1,398,987, issued December 6, 1921.

The invention is illustrated in the accompanying drawings in which Figure 1 shows 35 a reflector of my improved type in vertical section. Figure 2 is a front view of the reflector shown in Figure 1 and Figure 3 is a view on an enlarged scale taken on line 3—3 in Figure 2.

The type of reflector that I have shown consists of an upper reflector 10 and a lower reflector 11, which, while they may be of the parabolic type, are illustrated as of the 40 kind that will reflect rays passing from the filament 12 of the lamp so that they are inclined downwardly relative to the horizontal axis of the reflector.

These upper and lower halves of the reflector unit of the headlight are joined in 45 horizontal plane through the axis of revolution and I show a horizontal dividing plate 13 with a small shield 14 for preventing di-

rect rays from the filament from proceeding upwardly and forwardly from the lamp. 55

On the reflector I place flattened portions 15, these being disposed on what might be termed vertical quadrants of the lamp leaving the side portions 16, which might be called the horizontal parts of the reflector, 60 in their normal or unbroken curved form.

The flattened portions 15 are arranged radially projecting from the point adjacent the outer edge or forward edge of the reflector toward the centre for the desired 65 distance, it being desirable to space these flattened portions one from the other and I also usually arrange other flattened portions 17 which are placed between the portions 15, these portions 17 extending about midway toward the centre of the reflector. The usual way of forming these spaces is by simply flattening small radial strips of the reflector surface in planes at right angles to the axis of revolution. 70

When in operation, the flattened portions 15 and 17 of the reflector tend to diffuse and spread the light beam and as these reflecting surfaces are flat and not circular and are in planes intersecting at right angles to the 75 reflector axis, the light which strikes such flattened portions will be spread by an amount equal to the angle subtended by the width of the flute or flattened portion with the focus point which is represented by the filament 12. 80

The radial flattened portions placed in the upper and lower or vertical quadrants of the reflector will diffuse and widen the light beam in horizontal direction owing to the 85 fact that the spread must necessarily be at right angles to the radial direction of the flattened portion. 90

To prevent spreading the beam and diffusing it in substantially vertical planes, I 95 place these flat reflecting portions only in the top and bottom portions of the reflector.

It is understood that the flattened portions refer to such portions in the metal which are flattened in planes at right angles with the 100 axis of revolution of the reflector whereas the other portions of the reflector are circular and in these planes. In the planes which include the horizontal axis of revolution of the reflector, the intersections with 105 the metal comprising the flattened portions

in each case are curved substantially parallel to the curves on the other portions of the reflector.

I claim:

5 1. A reflector with upper and lower halves both designed to direct rays downward in relation to the axis of the reflector, the opposed vertical quadrants of the reflector having radially arranged flattened portions.

2. A reflector with upper and lower halves 10 both designed to direct rays downward in relation to the axis of the reflector, the opposed vertical quadrants of the reflector having radially arranged spaced flattened portions, the alternate portions being shorter 15 in length than the others.

In testimony where of I affix my signature.
CHESTER N. WEEMS.
